UNITED STATES PATENT OFFICE.

PATRICK W. REARDON, OF SAN JOSÉ, CALIFORNIA.

DRY ORE SEPARATOR.

SPECIFICATION forming part of Letters Patent No. 276,710, dated May 1, 1883.

Application filed February 10, 1883. (No model.)

To all whom it may concern:

Be it known that I, PATRICK W. REARDON, of San José, county of Santa Clara, State of California, have invented an Improved Dry Ore Separator; and I hereby declare the following to be a full, clear, and exact description thereof.

My invention relates to certain new and useful improvements in dry ore separators. These improvements relate particularly to that class of separators shown in Letters Patent No. 263,808, issued to me September 5, 1882; and it consists in sundry details of construction, all of which will be hereinafter fully described and claimed.

The object of my invention is to effect a greater saving of the precious portions of the ore.

Referring to the accompanying drawings, Figure 1 is a longitudinal vertical section of my machine. Fig. 2 is an end view of the riffle-box. Fig. 3 is a horizontal section taken on line Y Z, Fig. 1. Fig. 4 is a detail, showing means for vertically adjusting the lid of the riffle-box. Fig. 5 is a detail section, showing the hopper-regulating mechanism and the connection with riffle-box.

A represents the frame of the machine, at one end of which are posts B, from which is suspended the riffle-box C, by means of spring-hangers c, to allow a vibration to be imparted to said riffle-box. This riffle-box consists of a three-sided open-ended frame, a, and a lid, b.

The bottom of the frame is provided with a broken surface formed by a series of angular cross-pieces or riffles, d, formed in one piece, or separately, in such manner as to present a short steep face and a longer gentle incline opposite. They resemble right-angle triangles lying upon the hypotenuse, as shown.

Across the face of each riffle, near its top, is secured a cleat, d', for the heavier material to lodge against. The cover or lid b is a flat piece provided near each side, underneath, with longitudinal grooves b', for fitting down over the sides of the box below, Fig. 4. In the sides of the box, under these grooves, are small screws e, which, when turned down, allow the lid to fit down fully, and when turned up raise it somewhat to narrow or widen the passage above the riffles, for a purpose I shall explain, Fig. 4.

Mounted in the frame, under the riffle-box, is a cross-shaft, D, to which power is to be applied by any suitable means. This shaft has an eccentric, f, near each end, with which are connected the pitmen E, the other ends of which are secured to the rear under side of the riffle-box. By these means a longitudinal vibration is imparted to the riffle-box.

Set upon the front portion of the frame A is a box, F, the top of which inclines downwardly to the front, its sides converging to the front. In the rear the box is of equal width with the riffle-box; but at the front it is much smaller, because of its inclined top and converging sides. Across its rear is made a slot, g. A wide flat pipe, G, connects the front open end of the riffle-box with the box F through slot g. This connection is here shown as made by providing each end of the pipe G with flanges and clamping said flanges between blocks H, secured upon the front of the riffle-box and upon the rear end of box F, as shown, Fig. 5. The box F being stationary and the riffle-box having a vibratory movement, it will be seen that this connecting-pipe G must be elastic or extensible. For this reason I now construct it of rubber, though any suitable elastic or yielding material might answer; or it might be made otherwise and rendered extensible by means of suitable mechanical devices.

Within the box F, which simply serves as a protector, is a wind-box, I. This consists of a bottom and a top of the same shape as and let into the sides of box F, in order to use said sides to form its own sides. Both bottom and top are inclined upwardly toward the front, though the top has the greater inclination, thus making the box lower at the rear than in front. This box has therefore a wide back and a narrow front, because of its converging sides, and it has also a shallow back and a deep front, because of the different inclinations of top and bottom. The rear edge of its bottom is brought right up to the lower edge of the slot g in box F; but its top is stopped short to allow the entrance of the base of the ore-hopper J. This hopper may be formed separate from the box F, or it may be formed within it by means of an inclined back board, j. The lower edge of this board comes down to the forward edge of the top of wind-box I. The ore in the hopper

passes through its base down into the rear end of the wind-box, immediately behind the slot or aperture *g*.

In order to regulate the feed of ore I have the following: The lower portion of the wall *j* is cut out, and has fitted upon it a sliding plate, *k*, the lower edge of which is cut on a bevel to enable it to lie flush against the vertical wall of the hopper when pushed down far enough, Fig. 5.

K is a threaded bolt, connected with the top of the sliding plate *k* by means of a swivel nut or joint. It passes up through a socket in the wall *j*, through a stationary nut, *l*, above, and is provided with a handle or crank-wheel on top. By means of this bolt the sliding plate *k* may be adjusted up or down to open the base of the hopper to its full width, to close it completely, or to regulate the opening as desired. An overlapping plate or strip, *p*, covers the joint of the sliding plate *k*.

L is a blower driven by suitable power, and connected with the front end of the wind-box *I*.

It will be seen that the riffle-box has a downward inclination to the rear, likewise the connecting-pipe *G* and the wind-box *I*. This facilitates the operation of the device, which is as follows: Ore is placed in the hopper, and its discharge is regulated by the adjustable plate *k*. The wind (a constant blast) is forced into the wind-box, and, by reason of the shape of said box, spreads itself laterally, while contracting vertically, so that its force is equalized upon the body of ore in front of it and its full effect delivered to drive it through the slot or aperture *g* and down through connecting-pipe *G* into the riffle-box. This box, having a vibratory movement, tends to settle the ore, so that the steady current of air passing along the upper portion of the box will carry off the light particles. If any of the heavier particles are caught, they will not be carried far before they are lodged below the cleats *d* on the riffles *d*.

In this device the air-current is not employed for effecting the actual separation by driving the lighter portions up an incline which proves too steep for the heavier portions, but for the purpose of providing a means for carrying off such lighter portions as may be kept within its influence by the vibration of the box. For this reason the upper portion of the passage through the box is smooth, and not tortuous, so that the

wind will not be directed so much on the riffles, and will leave the ore free to settle. The riffles are to prevent the heavier particles which may be caught by the steady blast passing through above from being carried away.

By the vertical adjustment of the lid of the riffle-box, heretofore referred to, I increase or diminish the air-passage through the box in order to regulate the force of the wind at different periods of the operation, or at different points in the riffle-box. The box *F* protects the wind-box, and by its sloping top *F'* prevents débris from lodging upon it.

Having thus described my invention, what I claim as new, and desire to secure by Letters Patent, is—

1. In a dry ore separator, the riffle-box *C*, consisting of the three-sided open-ended frame *a*, having riffles *d*, and the cover or lid *b*, and the means for vertically adjusting said cover, consisting of the screws *e* in the sides of the frame *a* and the grooves *b'* in the cover, substantially as and for the purpose herein described.

2. In a dry ore separator, the vibrating riffle-box *C*, in combination with the stationary ore-hopper *J*, the wide rubber pipe *G*, connecting the two, and means for forcing an air-current through said pipe to carry the ore into the riffle-box, substantially as herein described.

3. In a dry ore separator, the vibrating riffle-box *C*, an ore-feeding device, blast-producing means, and a connecting-pipe, in combination with the wind-box *I*, the sides of which converge to the rear, while the top and bottom converge to the front, whereby is formed a wide shallow front opening communicating with the connecting-pipe, and a narrow deep rear opening communicating with the means for forcing an air-current into said box, substantially as herein described.

4. In a dry ore separator, the ore-hopper *J*, provided with the sliding regulating-plate *k*, and the screw *K*, in combination with the wind-box *I*, the vibrating riffle-box *C*, and the elastic pipe *G*, connecting the riffle-box with the wind-box and ore-hopper, substantially as herein described.

In witness whereof I hereinunto set my hand.

PATRICK WILLIAM REARDON.
